2 SHEETS—SHEET 2.

UNITED STATES PATENT OFFICE.

GEORGE A. HANLY, OF ELGIN, ILLINOIS.

PNEUMATIC VALVE APPARATUS.

1,152,810.

Specification of Letters Patent.

Patented Sept. 7, 1915.

Application filed November 27, 1914. Serial No. 874,178.

To all whom it may concern:

Be it known that I, GEORGE A. HANLY, a citizen of the United States, residing in the city of Elgin, county of Kane, and State of Illinois, have invented certain new and useful Pneumatic Valve Apparatus, of which the following is a specification.

My invention relates to means for controlling a liquid discharge through the utilization of an air body interposed between the liquid body and the discharge passage.

The principal objects of the invention are to provide efficient, durable and simple means for controlling a fluid discharge; further, to provide valve mechanism for a liquid discharge in which there is an absolutely tight seal between the liquid and the port of discharge, and a seal which does not depend upon the grinding or fitting together of valve elements, thus avoiding difficulties and disadvantages in manufacture, use and repair; further, to provide an obstruction between the liquid body and the port of discharge which automatically conforms to varying pressure conditions of the fluid body and automatically provides escape for the liquid when the pressure, or in other words the quantity of the liquid in the container, becomes greater than that of a predetermined amount; also to provide pneumatic valve apparatus which may be automatic in periodically discharging a predetermined quantity of liquid, or which may be hand-controlled for discharge only as desired; further, and more specifically to provide a flushing-valve mechanism for water closets, or where similar flushing operations are desired, having features and advantages hereinabove pointed out, and which is of simple construction, operates reliably and efficiently, is adapted for use in the present form of well known apparatus calling for flushing operations, and overcomes many disadvantages incident to more or less complicated devices involving valve seats, etc., heretofore used.

Other objects and advantages will appear hereinafter.

In the accompanying drawings, which form a part of this specification, I have illustrated a simple embodiment of my invention as applied in flushing a device such as a water closet, and the ensuing description will relate more specifically to such use, although the invention is susceptible of vari-

ous other uses and applications and may be embodied in structure radically different from that illustrated, which illustration is intended merely to show one thoroughly 60 practical and efficient embodiment of the invention and afford a teaching of the application of the principle or principles involved.

In these drawings Figure 1 is a vertical 65 and substantially medial section longitudinally through a flushing tank and my improved pneumatic control mechanism therein; Fig. 2 is a similar view but with the operative parts in another operative position; Fig. 3 is a transverse vertical section of the tank as on the line 3-3 of Fig. 1, showing also, mainly in section, the trap and its connection to a closet bowl to be flushed, the end of the air pocketing device being 75 shown in full lines for convenience of illustration; Fig. 4 is a perspective view of the air pocketing hood-like element; Fig. 5 is a view, partly in section, of the trap element at right angles to its position in Fig. 3; and 80 Fig. 6 is a small sectional elevation similar to Fig. 1, showing a modification of a frame element and the pivotal arrangement of the air-pocketing hood thereto, this arrangement being found quite advantageous in 85 practice.

The present embodiment of the invention is illustrated in connection with apparatus for flushing a water closet bowl, in which use the tank element 10 and the bowl 11 may 90 be of the usual and well known construction. A water supply pipe 12 with a portion 13 thereof depending so as to conduct water to the lower part of the tank, and having the valve 14 controlled by the float 15 is also 95 of well known form and requires no detailed description, it being understood that as the water in the tank is discharged the valve 14 will automatically admit a further supply thereto, and that when the surface of the 100 water again reaches a predetermined height, as at 16, the supply will be cut off by the action of the float 15.

The element for discharging water from the tank includes the trap 17 terminating in the pipe-like element 18 having the discharge orifice 19. This discharge element 18 is suitably a casting, and is provided with an annular flange 20 which fits upon an annular gasket or packing element 21 while 110 the portion 22 is threaded to receive the interiorly threaded upper end portion 23 of

the trap element 17, a washer 24 providing a seat for the element 23. It will thus be seen that the bottom of the tank is tightly clamped and sealed against water leakage at this joint.

The hood-like element, cover or cap 25 preferably of sheet metal, has a top wall 25^a, front wall 25^b, side walls 25^c, end wall 25^d, bottom walls 25^e and intermediate wall 25^f

10 preferably as illustrated, these walls being connected together with air-tight joints, so that air pocketed beneath the same will not escape at the top, sides or ends. The end A of this device, however, is open throughout 15 its entire bottom portion, that is, from the intermediate wall 25^f to the end wall 25^b and between the side walls 25^c, which opening I will denominate 26. This hood-like element 25 is pivoted on opposite sides as at 20 27, to the frame 28, which frame is turned upward at 28^a and has the cross piece 28^b. The frame 28 is pivoted, as at 29, so as to swing upward into the dotted line position of Fig. 1. This element 25 constitutes a 25 housing, cap or cover for the discharge element 18 which projects into the hollow interior of the cap 25 through the opening 26, and, in my present practice in the form of device illustrated, the discharge orifice 19 is 30 about an inch from the top 25^a of the cap element when in the normal full line position of Fig. 1, the discharge element 18 projecting about three inches above the bottom of the tank.

35 The cover element 25 is normally in the position shown in Fig. 1 just before a flushing operation, and is maintained in such position by the rod 30 having the portion 31 formed as a stop and adapted to engage both 40 the projecting portion 25^e of the cover element and the cross piece 28^b of the frame element. This rod 30 terminates in a shaft 30^a pivoted in the side walls of the tank, projecting through one wall of the tank and carrying the handle 32 and the counterweight 33 for lever action, the handle being shown in dotted lines in Fig. 1. It will be appreciated that by moving the handle in a downward direction the latch element 31 45 will be moved to the left when arranged as in Fig. 1 and that thereupon both the cover element 25 and the frame element 28 will be released.

50 It will readily be appreciated that when water is introduced into the tank 10, provided there is water in the trap element 17 (which there always is after a flushing operation), a quantity of air will be pocketed beneath the cap or cover 25 and within the 55 hollow interior 19^a of the discharge element, and that there will be a water-line, as 35, within the cap element 25, and that the air in the space above the surface 35 in Fig. 1 will act as a dam or obstruction to the rising 60 of the surface 35. In Fig. 1 this surface

35 is shown as at about its normal position when the surface of the water outside of the cap 25 is at its predetermined normal height, as at 16. It will also be appreciated that air will begin to pocket in the cap 25 70 as soon as the lower edges of the walls 25^b, 25^c and 25^d defining the opening 26 are completely submerged by water rising in the tank. These lower edges, as shown, are on a common plane. As the head of water outside the hood-like element 25 becomes greater, the air in the element 25 becomes more compressed, and some of it is forced downward into the leg 17^a of the trap 17, forcing the water down also, until the water-line in leg 17^a is fairly close to the lower end 36^a of the partitioning wall 36 between the legs 17^a and 17^b of the trap, or in other words until it is close to the turn in the trap, say at 38, Fig. 3. There is thus a column of water in the leg 17^b of the trap reacting against the head of water in the tank, and these two bodies of water have thus interposed between them a quantity of air so held as to balance their respective gravitation forces when the height of the water from the discharge opening 37 of the trap to the point 36^a, is equal to the distance between the surface 35 within the air pocketing device and the surface 16, or, in other words, when the vertical distance *c*—*d* is equal to the vertical distance *a*—*b* of Fig. 3. 80

85 When the head of water in the tank is thus balanced against the head in the leg 17^b of the trap the surface 35 is still somewhat below the discharge orifice 19, and the surface 38 in the trap is still somewhat above the turn in the trap of the point 36^a, and the water is bound to remain in these relative positions either until additional water 90 is added to the contents of the tank or until some of the imprisoned air is discharged.

95 Before proceeding to describe further the operation of the device I will call attention to the air intake opening 40 in the lower end portion of the end B of the air pocketing device, the capacity of this opening 40 being regulated by any suitable small valve device, shown as a threaded valve stem 41 having the head 42. I also call attention to the counterweight 43 on the end B, which is of sufficient weight to tilt the end A upward on the pivots 27. The ends A and B are 100 preferably considerably out of balance with respect to the pivot 17. In my practice I prefer to have the difference such that it would require about six or eight ounces at the point A substantially to balance this element on its pivots 27. The weight of the counterweight 43 may be varied within some 105 limits, but should be of sufficient weight to prevent the end A from descending more rapidly into the dotted line position of Fig. 2 than the surface of the discharging water outside of and around the open edges of this 110

element 25 falls, and must not be so heavy as to prevent the end A from being drawn down as the water falls. To prevent this last mentioned operation, however, would 5 require a counterweight considerably heavier than is necessary for the successful operation of the device.

Assume the parts to be in their normal positions just before a flushing operation, as 10 in Fig. 1, the tank being substantially filled with water and the float 15 having cut off the further supply by closing the valve 14. If the knob or handle 32 be now depressed, the catch element 31 releases the air cap 25 15 and the frame 28 whereupon the counterweight 43 causes the end A of the cap element 25 to rise until the end B strikes the frame 28, as in the full line position of Fig. 2, whereupon the frame 28 also rises, moving 20 on the pivot 29, due to the buoyancy of these parts by reason of the imprisoned air within the element 25, until the hood and frame are substantially in the dotted line positions of Fig. 1, and the imprisoned air 25 has escaped into the space above the surface 16. The discharge through the orifice 19 begins almost instantly the catch 31 is 30 actuated. As soon as the pocketed air has escaped, the buoyancy of the air cap 25 and frame 28 is of course destroyed, and these parts thereupon immediately begin to settle through the water not yet discharged and in a brief space of time have returned 35 to the positions shown in full lines in Fig. 2, the end piece 28^b of the frame 28 forcing the rod 30 into its normal or substantially vertical position, the frame being automatically caught under the catch portion 31 of this catch and release mechanism. While 40 the parts are in the position last mentioned there is no air beneath the hood-like element 25, all of the space being now occupied by water, which thus has free access to the discharge orifice 19, and the discharge continues 45 without any change in the relative position of the parts until the surface of the water in the tank outside of the air cap 25 has fallen substantially to the lower edge of the end wall 25^b, or substantially to the 50 level 44 of Fig. 2. Owing to the fact that the element 25 has been completely filled with water there is a tendency to form a vacuum in the end A of the element 25 when in the full-line position of Fig. 2 and 55 the water outside the inverted cup element 25 has fallen below the top thereof, or, for instance to the level 44. This tendency to produce a vacuum causes the end A to descend, keeping the lower edges thereof 60 always beneath the falling surface of the water. It also causes the water to flow from outside the element 25 upward into it, and the end A continues to descend until the hood element 25 is substantially in the 65 dotted line position of Fig. 2, in which po-

sition its further downward movement is stopped by a stop element, as 45, adapted to space the lower edges of the open end A somewhat, say about one-fourth of an inch, from the bottom of the tank. This tendency to produce a vacuum is occasioned by 70 the difference in height between the point of discharge into the apparatus flushed and the orifice 19, that is, the vertical distance e-f of Fig. 3. A siphon is thus formed 75 and has been put into operation through the initial discharge from the tank, and the siphoning action continues until substantially all the water is withdrawn from the tank—say to within a quarter of an inch of 80 the bottom plus the water still within the hood element 25. While the end A is descending in the operation last described the counterweight 43 retards its descent and maintains the lower edges of the end A just 85 at or slightly beneath the falling surface outside the element 25.

We must now revert to an earlier stage in the descent of the end A in order to understand another feature. As the end A descends, the end B naturally rises, and in due course the air intake opening 40 comes above the surface of the water around the end B. The end B is still filled with water, as, without the presence of air in the closed 90 end the water therein can not escape, and thus far in the operation no air has been admitted to the interior of the element 25. Now that the intake opening 40 is exposed, however, air enters the element 25 at this 95 point and the water in the end B begins to flow toward the orifice 19. Water is now being supplied to the discharge orifice 19 from both ends A and B. Dependent upon the amount of air admitted through the 100 opening 40 the descent of the water in the now somewhat elevated end B will be rapid or slow. I prefer to have such descent slow, as, while thus a relatively small quantity of water is withdrawn from the end B, the end A is still furnishing a relatively 105 large quantity to the discharge orifice 19, and the tank may thus be emptied more completely. The discharge continues without interruption until the descending surface of the water in the end B comes to the 110 discharge orifice 19, and, as the tendency to produce a vacuum beneath the hood 25 is now overcome by a supply of air to the discharge orifice, and as the holding, sustaining 115 and raising force for the water in the end A is now removed, the water in end A immediately falls back to a natural level within the tank, which is below the air intake opening 40 when the cap is in its normal 120 substantially horizontal position which position it at once regains through the influence of the counterweight 43, the projection 25^c being caught by the latch element 31. All of the water is now out of the end 125 130

B also, as all of the water in the hood 25 has found its normal level in the bottom of the tank, and the air pocketing element 25 is now occupied only by air. The supply pipe 12, 13 has been providing additional water to the interior of the tank from the time the float 15 descended sufficiently to open the valve, but the flow through the discharge orifice 19 being many times greater than that through the supply pipe the additional water entering the tank has had no effect to prevent any of the operations described, but has merely provided some additional water to be discharged. The supply flow continuing, however, after the air pocketing device 25 is in its substantially horizontal position, as in Fig. 1, the water soon rises to the air intake opening 40, whereupon this opening is sealed and a quantity of air is again entrapped or imprisoned sealing the orifice 19 as before. The water forced around the bend 36^a and out of the leg 17^a of the trap when the tank is again being filled supplies a suitable amount of water to the vessel being flushed, as when a re-fill of that vessel is desired.

The device illustrated may readily be adapted to act as an automatic flushing device by merely adjusting the float 15 so that it will operate on a sufficiently higher level so that the head of water within the tank is sufficient to force the water in the leg 17^a of the trap down to the turn 36^a of the trap so that some air may escape into the leg 17^b and permitting the surface of the water within the element 25 to rise sufficiently to overflow the edge of the discharge pipe 18, when a complete discharge takes place. As soon as a quantity of air is heard bubbling through the leg 17^b of the trap the flushing operation begins. In the specific apparatus shown, if I add as much as one inch of water to the normal surface in the tank the device will thus flush automatically. This fact provides security against overflowing the tank should a leak occur in the supplying valve 14, and provides an indicator of such flow, which leakage may be promptly remedied and thus the constant leakage avoided which through a month or more would result in a considerable loss of water. Another way to provide the automatic flushing in the device illustrated, the arrangement otherwise being the same, would be to shorten the trap from the normal water line *c-f* thereof to the bottom, thus reducing the pressure necessary to force a quantity of air around the bend for its escape as already pointed out.

The trap 17 is preferably a casting and is preferably formed to provide a gradually enlarging interior toward the bottom, as illustrated, to provide a freer flow therethrough. It may, however, be a pipe of uniform diameter. In practice I give the

discharge orifice 19 a diameter of two and one-fourth inches, the discharge orifice 37 of the leg 17^b a diameter of two inches, and the capacity of the lower portion of the trap equal to that of a pipe of a two and one-half inch diameter. The distance *c-d* is about ten inches and the distance *e-f* eight to ten inches. The flush box or tank 10 is of a standard construction about twenty by five by sixteen inches. The proportions of the element 25 are well shown in Figs. 1, 2 and 3. The invention with respect to this specific application thereof is not limited, however, either to shape or proportions of the elements shown, these proportions being given merely for guidance in constructing the specific device set forth.

Reference should be had to the appended claims to determine the scope of this invention, and all structural embodiments of the same are contemplated by me as fall within the scope of these claims.

I claim:

1. The combination of a tank having a source of liquid supply, a discharge element projecting upward in said tank, an air pocketing device having a downward opening in one end portion thereof and being substantially closed at another end portion thereof, said two portions being open to each other, the downwardly open portion of said device being adapted substantially to surround said discharge orifice, said air pocketing device being pivotally mounted whereby the same may move upward to discharge pocketed air, and also to tilt whereby said open portion moves downward from its normal air pocketing position, the substantially closed end portion of said hood-like device being adapted to tilt upward and having an air intake opening adapted to rise above the surface of the liquid in said tank when the open end of said hood-like device tilts downward, the open portion of said hood-like device together with said discharge pipe constituting a siphon when said hood-like device is in a downwardly tilted position, and means for releasably holding said hood-like device in its normal air pocketing position.

2. The combination of a tank for a liquid, a discharge element having a discharge orifice in said tank, a support pivotally mounted, a hood-like device pivotally mounted intermediate its ends on said support, said hood-like device having side, end and top walls, and a bottom wall over a portion thereof, said hood-like device being open downwardly at a portion thereof, said open portion being adapted to tilt downward, said open portion substantially surrounding the discharge orifice in said discharge pipe and adapted to pocket a quantity of air thereabout, means for releasably holding said hood-like device and frame in normal

air pocketing position, the open portion of said hood-like device and said discharge pipe constituting a siphon when in such downwardly tilted position, the more ⁵ closed portion of said hood-like device having provisions for admitting air thereinto when the liquid in said tank is flowing through said discharge orifice by siphonic action, such admitted air being adapted to break such siphonic action and to constitute an obstruction about said discharge orifice when the liquid in said tank again rises above said discharge orifice.

3. The combination of a tank for a liquid, ¹⁰ a discharge element in said tank, and a pneumatic valve apparatus comprising in combination a support adapted to be pivotally mounted to swing upward in said tank, a hood-like device pivoted intermediate its ¹⁵ ends on said support, one end portion of said hood-like device being substantially a pocket having side walls, a top wall, end wall and a bottom wall, said end portion having an air intake opening, the other end ²⁰ portion of said hood-like device being open normally downward and adapted to surround a portion of such pipe in air pocketing relation when normally in use, said two portions being open to each other, and means ²⁵ for releasably holding said hood-like device in normal air pocketing position.

4. The combination of a tank for a liquid, a discharge element therein, and a pneumatic valve apparatus comprising a hood-³⁰ like device pivoted intermediate its ends, one end portion thereof constituting a pocket open toward said other end portion, and having an air-intake opening, the other end portion also constituting a pocket open ³⁵ downwardly and adapted to surround such discharge element in air pocketing relation, and means for releasably holding said hood-like device in air pocketing position about such discharge element.

45 5. The combination of a tank for a liquid, a discharge element therein, and a pneumatic valve apparatus comprising a hood-like device pivoted intermediate its ends, one end portion thereof constituting a ⁵⁰ pocket open toward said other end portion, and having an air-intake opening, the other end portion also constituting a pocket open downwardly and adapted to surround such discharge element in air pocketing relation, ⁵⁵ the end portion which has said air intake opening having a counterweight adapted normally to tend to cause said end portion to tilt downward, and means for releasably holding said hood-like device in air pocket-⁶⁰ ing position about such discharge element.

6. The combination of a tank for a liquid, a discharge element therein, and a pneumatic valve apparatus comprising a hood-like device pivoted intermediate its ends, ⁶⁵ one end portion thereof constituting a

pocket open toward said other end portion, and having an air-intake opening, the other end portion also constituting a pocket open downwardly and adapted to surround such discharge element in air pocketing relation, ⁷⁰ the end portion which has said air intake opening having a counterweight adapted normally to tend to cause said end portion to tilt downward, the downwardly open end portion of said device having its normally ⁷⁵ lowermost edges so formed that they are on a substantially horizontal plane when said open end is tilted downward, and means for releasably holding said hood-like device in air pocketing position about such discharge ⁸⁰ element.

7. The combination of a tank for a liquid, a discharge element having a discharge opening in said tank, a trap in said discharge element adapted to contain a quantity of liquid, a hood-like element over and around said discharge opening, said hood-like element having air-tight top and side walls and open at the bottom at one end portion thereof and substantially closed at the ⁸⁵ bottom sides and top at the other end portion thereof, said two portions being open to each other, said hood-like element being adapted to pocket a quantity of air about said discharge opening, said hood-like element being pivotally mounted intermediate its ends to tilt, means for releasably holding said hood-like element in air pocketing position when the surface of the liquid in said ⁹⁰ container is substantially above said discharge opening, the open end portion of said hood-like element being adapted to tilt downward when the liquid in said tank falls below said discharge opening, said hood-like element having provisions for admitting air ⁹⁵ to the closed end of said hood-like element when that end is tilted upward, said hood-like element being weighted to resume its normal air-pocketing position when air is admitted to said closed end in such raised ¹⁰⁰ position.

8. The combination of a tank adapted to contain a liquid, a discharge element projecting into said tank and having a discharge orifice therein, said discharge element having a trap normally below said discharge orifice, an inverted hood-like device adapted to imprison a body of air about said discharge orifice and thereby to seal the same against liquid flow therethrough, said ¹¹⁵ hood-like device being pivotally mounted intermediate its ends whereby an end portion thereof may move upward and downward from its normal air imprisoning position, said end portion comprising walls normally ¹²⁰ about said discharge orifice and providing an opening for the escape of such imprisoned air when said end portion moves upward whereby liquid may flow through said discharge orifice, said hood-like device hav- ¹²⁵

ing another opening, this being in the opposite end portion from that mentioned, adapted to provide an intake of air to the interior thereof when said portion moves downward 5 from its normal air pocketing position.

9. The combination of a tank adapted to contain a liquid, a discharge element having a discharge orifice in communication with the interior of said tank, said discharge element having a trap adapted to contain a quantity of liquid, said trap having a longer leg and a shorter leg, said longer leg being directly in communication with said discharge orifice, hood-like means pivotally mounted in said tank whereby an end portion thereof is normally about said discharge orifice, said end portion being adapted to tilt upward and downward from its normal air pocketing position, said hood-like means being adapted to imprison a body of air in 10 said discharge element so as to provide an obstruction to the passage of liquid from said tank thereinto, said hood-like means having provisions for discharging air therefrom when said end portion tilts upward, said hood-like means having provisions for admitting air to its interior when said end portion thereof tilts downward from its said normal air pocketing position, and 15 means for maintaining said hood-like device releasably in normal air pocketing position against the upward pressure of air pocketed therein.

10. The combination of a tank for a liquid, a discharge element having an opening in communication with the interior of said tank, said discharge element having a normally arranged trap normally below said tank and adapted to contain a quantity of 20 liquid, a hood-like device pivotally mounted intermediate its ends, a pivotally mounted frame on which said hood-like device is mounted, said device being adapted to pocket a body of air in said discharge element and about the opening thereof into said tank, means for holding said device releasably in air entrapping position against the upward pressure of air therein, one end of said device being adapted to tilt downward 25 when water is discharging through said discharge element, said downwardly tilting end then constituting a siphon together with said discharge element, the other end tilting upward the while, said other end having an opening for admitting air to the 30 interior of said device to break the siphonic flow when said opening therein rises above the descending surface of the water in said tank.

60 11. The combination of a container for a liquid and having a source of liquid supply therefor, liquid discharge means including

a liquid trap, said discharge means having a discharge orifice within said container in an upwardly extending portion of said discharge means, hood-like means pivotally mounted whereby one end thereof may tilt upward and downward from its normal air pocketing position in said container, said end portion of said hood-like means being 65 adapted to cover and surround said orifice and to pocket air about the same when the liquid level in said container is below the level of said orifice and rising in said tank, said liquid discharge means constituting one 70 leg of a siphon, said hood-like means constituting another leg thereof, said hood-like means having provisions for discharging air therefrom when said end thereof tilts upward and the liquid in said container is 75 above said orifice, said hood-like means having provisions for admitting air to the interior thereof when said end which tilted upward tilts downward and liquid is discharging through said orifice, and means 80 for maintaining said hood-like means releasably in normal air pocketing position 85 against upward pressure of air pocketed therein.

12. The combination of a tank having a 90 source of liquid supply, a discharge pipe projecting upward in said tank and having a discharge orifice therein, a hood-like device having an open portion substantially surrounding said discharge orifice, a support pivotally mounted to move upward 95 in said tank, said hood-like device being pivotally mounted intermediate its ends on said support, operable means for releasably holding said hood-like device in normal air pocketing position against upward movement, said hood-like device and frame being adapted to swing upward when water is in said tank and air is pocketed in 100 said hood-like device and said holding means are operated to release said hood-like device, the open portion of said hood-like device being free of said holding means to tilt downward on said support from its normal air pocketing position when water is 105 discharging through said orifice, said discharge pipe and said hood-like device constituting a siphon when the open portion of 110 said hood-like device is in a downwardly tilted position, said hood-like device having provisions for admitting air thereinto when said open portion is tilted downward and the opposite portion thereof rises above the surface of the water in said tank.
